US0D1102861S

(12) **United States Design Patent** (10) **Patent No.:** **US D1,102,861 S**
(45) **Date of Patent:** **** Nov. 25, 2025**

(54) **KNIFE SHARPENER ASSEMBLY**

(71) Applicant: **Kadijah Siddiqui**, Fremont, CA (US)

(72) Inventor: **Kadijah Siddiqui**, Fremont, CA (US)

(**) Term: **15 Years**

(21) Appl. No.: **29/842,750**

(22) Filed: **Jun. 15, 2022**

(51) **LOC (15) Cl.** **08-05**

(52) **U.S. Cl.**

USPC **D8/93**

(58) **Field of Classification Search**

USPC D8/14, 35, 63, 90, 91, 93

CPC B24B 3/00; B24B 3/36; B24B 3/54; B24D

15/02; B24D 15/06; B24D 15/08; B24D

(57) **CLAIM**

The ornamental design for a knife sharpener assembly, as shown and described.

DESCRIPTION

FIG. 1 is a front view of a knife sharpener assembly, showing my new design;

FIG. 2 is a right side view thereof;

FIG. 3 is a perspective view thereof;

FIG. 4 is another perspective view thereof;

FIG. 5 is a top view thereof;

FIG. 6 is another perspective view thereof;

FIG. 7 is a front view of the angle guide portion of the knife sharpener assembly of FIG. 1;

FIG. 8 is a back view thereof;

FIG. 9 is a right side view thereof;

FIG. 10 is a perspective view thereof; and,

FIG. 11 is another perspective view thereof.

1 Claim, 6 Drawing Sheets
